UNITED STATES PATENT OFFICE.

NORWOOD V. STANSFIELD, OF BALTIMORE, MARYLAND.

BAG SEAL.

Application filed June 19, 1922. Serial No. 569,434.

To all whom it may concern:

Be it known that I, NORWOOD V. STANSFIELD, a citizen of the United States, residing at Baltimore city, State of Maryland, have invented certain new and useful Improvements in Bag Seals; and I do hereby declare the following to be a full, clear, and exact description of the invention, such as will enable others skilled in the art to 10 which it appertains to make and use the same.

The present invention relates to improvements in bag seals in which a lead or other malleable body is used to secure the cord 15 which passes about the neck or mouth of the sack in which money is placed for transportation and shipment.

Heretofore considerable difficulty has been encountered in the opening of the bag by its 20 authorized recipient due to the fact that in using a knife to cut the cord, the present seal body is so disposed and arranged with reference to the cord that this action jeopardizes the material of the bag and even 25 where the greatest care is exercised it is found that oftentimes the fabric of the bag is cut by the knife during the severing of the cord and the bag thus rendered useless and having to be discarded.

It is an object of the invention to provide 30 a sealing body in combination with a fastening cord, which will be so constructed and arranged as to permit of the severing of the cord by the use of the knife without 35 endangering the fabric of the bag, and at the same time to render this operation easier and less tedious, all the while providing an effective seal and a tight closure.

Other objects of the invention are to 40 economize on the amount of material used in the seal which is expensive, to render the cord more accessible for both fastening and severing, and in general to provide an article of this nature which may be more readily handled and which will promote the longer life of these bags which are also quite costly.

With the foregoing and other objects in view the invention will be more fully described hereinafter and more particularly pointed out in the subjoined claim.

In the drawings wherein like parts are designated by like symbols throughout the several views,

Figure 1, is a side view of a bag having

the improved seal in place on the neck or mouth thereof.

Figure 2, is an enlarged edged view of the seal prior to its bending or offsetting.

Figure 3, is a central sectional view taken 60 through the seal and fastening cord.

Referring more particularly to the drawing, 1 designates the bag made of an appropriate fabric such for instance as money bags employed in banks for the transfer of 65 coin and currency.

According to the invention the improved seal comprises a solid body or block 2 of lead or some other relatively soft material capable of being bent or offset in order to 70 bind the cord therein. The body carries a pin 3 the head of which is embedded in the material of the body with its point projecting for a considerable distance beyond the inner end of the body for the purpose of 75 entering the material of the bag mouth. For convenience the end of the solid body toward the bag is referred to as the inner end of the body and that away from the bag as the outer end of the body. This pin 3 occupies 80 a substantially central position, or rather it lies coincident with the longitudinal center of the block projecting beyond its inner end. At the sides of the pin are the openings 4 and 5 to receive the end portions 6 and 7 of 85 the fastening cord which is formed into a pair of loops 8 and 9 embracing the bag mouth. The intermediate part of the cord or the bight 10 extends across the outer end of the seal body after passing through the 90 perforations 11 and 12 which parallel the openings 4 and 5 and are situated at the outer sides of the block and extending for only a short distance at the front part there- 95 of inasmuch as the intermediate and rear portions of the sides of the body are removed providing spaces having the sloping walls 13 and 14. These spaces at the sides of the block are deeper at the outer portion and are narrower towards the inner portion by 100 virtue of the inclination given the walls 13 and 14, in other words the side walls 13 and 14 converge outwardly or away from the inner end of the solid body.

When the loops 8 and 9 are engaged from the mouth of the sack as shown in Fig. 1 and the pin 3 duly inserted in place, the ends 6 and 7 of the cord are pulled outwardly through the openings 4 and 5 drawing the block 2 toward the bag permitting 110

the tightening of the loops and the complete closing of the bag mouth. After the final position has been arrived at, the seal body is placed in a suitable stamp or press 5 and the holes 4 and 5 are closed tightly against cord 6 and 7 and the seal body is bent or corrugated as shown in Fig. 1. In this way the sealing of the bag is brought about and it may be prematurely opened 10 only by tampering with the block 2 which will immediately show this fact.

When the bag arrives at its destination and an authorized employee of the receiving bank wishes to open it he applies a knife 15 along both spaces at the sides of the block where the cord is left exposed and the cord is severed at these points which is remote from the fabric of the bag. The knife is moved up and down at right angles to the 20 cord and when it comes suddenly through the cord, it will strike either of the inclined walls 13 and 14 and be directed away from the bag avoiding the possibility of cutting the fabric thereof. The laterally projecting 25 parts of the block 2 at the outer end thereof form shoulders to arrest the sliding movement of the knife on the inclined walls.

It will thus be appreciated that with a seal constructed according to the present invention the cord may be readily and con- 30

veniently severed with entire safety to the bag, but that the seal is rendered no less effective because of this construction and notwithstanding the advantages in this respect, its accomplishment is attended by the 35 considerable saving of lead which would otherwise occupy the spaces at the side of the body.

I desire it to be understood that I have shown and described a preferred and satisfactory embodiment of my invention, but obviously changes and modifications may be made therein without departing from the spirit of the invention, and I reserve the 40 right to make such changes and modifications as may be fairly included within the 45 scope of the following claim.

What I claim is:—

A bag seal comprising a solid seal body, 50 and a fastening cord looped about the bag and passing longitudinally through the seal body, said seal body having side walls converging outwardly away from the inner end of the seal body, the outer end of the body having shoulders projecting beyond the ends 55 of the side walls, to hold the cord in exposed position along said converging walls, substantially as described.

NORWOOD V. STANSFIELD.
